[57] CLAIM

The ornamental design of a telephone device, as shown and described.

DESCRIPTION

FIG. 1 is a top, front, and right side perspective view of a telephone device showing our new design;

FIG. 2 is a top view thereof;

FIG. 3 is a bottom view thereof;

FIG. 4 is a left view thereof;

FIG. 5 is a right view thereof;

FIG. 6 is a front view thereof; and,

FIG. 7 is a rear view thereof.

Broken lines are for illustrative purposes only and form no part of the claimed design.
